H. L. & M. A. CALDWELL,
SCREENED CRIB OR BED,
APPLICATION FILED MAR. 6, 1914.

1,175,409.

Patented Mar. 14, 1916.

UNITED STATES PATENT OFFICE.

HAROLD L. CALDWELL AND MARCUS A. CALDWELL, OF COLUMBUS, OHIO.

SCREENED CRIB OR BED.

1,175,409.

Patented Mar. 14, 1916.

Application filed March 6, 1914. Serial No. 823,019.

To all whom it may concern:

Be it known that we, HAROLD L. CALDWELL and MARCUS A. CALDWELL, citizens of the United States, residing at Columbus, in the county of Franklin and State of Ohio, have invented a certain new and useful Improvement in Screened Cribs or Beds, of which the following is a specification.

This invention relates to the improvement 10 of the screened crib or bed shown in the application of Samuel Caldwell and Harold L. Caldwell, filed Aug. 28, 1913, S. No. 787,074, and consists in an improvement upon and simplification of that construction 15 whereby the manipulation and operation of the cover frame are rendered easier and the cost of construction reduced.

In the accompanying drawing—Figure 1 is an end view of the crib. Fig. 2 is a top 20 plan view of the rear edge of the cover frame showing also the guides for the same. Fig. 3 is a detail of the upper right hand rear corner of the crib showing the cover frame supported in elevated opened position. Fig. 4 is a perspective view of the 25 same corner with the cover frame omitted. Fig. 5 is a perspective view looking at the inner side of the upper end of the channel member.

30 The construction generally is substantially the same as shown in said former application, that is to say it comprises a bottom frame, ends hinged thereto to fold above the bottom, sides having slip hinges connecting them to the bottom and adapting them to be folded one above the other and a cover frame having a sliding connection with one of the sides. The bottom, ends, sides and cover are covered with wire screen.

40 In the present instance the bottom frame is designated at 6, one of the ends at 10 and front and rear frames at 11 and 11^a respectively and the cover frame at 12. Secured to the ends of the rear frame 11^a is a pair 45 of channel members or guides 13 and 13^a formed of strips of sheet metal longitudinally rolled to form a securing lip 14, a pin groove 15 and a lip 16 bent inward at right angles to the securing lip 14 to form with

50 the crib's rear frame the main channel or groove for receiving the end edges of the cover frame when the latter frame is to be compacted with said rear frame. The cover frame has secured to it hinging pins 17 and 55 17^a that project a little beyond the ends of that frame and each of the guides 13 and

13^a is provided with an L-shaped slot having the horizontal branch lying partly in the lip 14 and partly in the forward wall of the pin groove or channel 15. The lower 60 end of the vertical part of said slot forms a seat for the hinging pin when the cover is raised to closing position. Punched out of the rear wall of the pin groove 15 is a tongue 18 (see Fig. 5) that forms not only 65 a stop to prevent the entire extraction of the cover frame from the main channel when that frame is raised but also a guide to direct the hinge pins 17 and 17^a into the horizontal parts of the L-shaped slot. When 70 the cover frame is raised in the main groove to bring the hinge pins against these stops 75 18 the cover frame is inclined and pulled forward until the hinge pins stand over the vertical parts of said L-shaped slots whereupon the whole frame may be dropped to closing position.

The position of the cover frame, when being raised, in the main channel is indicated by the broken lines in Fig. 3. To support the cover frame in open position, as for the purpose of temporarily removing the infant or adjusting the pillow or clothing, said frame is merely raised, as in opening the lid of a trunk, and turned back to a position slightly beyond the vertical where it will be supported by the inwardly turned lips 16 of the channel member as further depicted in Fig. 3. To put the cover frame from closing position into compacted relation with the rear frame the operation is the reverse of that obtaining in bringing the cover frame to closed position, that is to say the cover frame is raised to vertical position and then slightly lifted and moved 90 rearward to remove the hinge pins from the vertical part of the L-shaped groove and through the bent horizontal part into the pin groove 15 after which the cover frame can be lowered to coincide substantially 95 with the rear frame. Where the pin groove or guide is formed as a channel the pins are inclosed and prevented from doing injury in manipulation and the whole channel member is stiffer and stronger by reason of 100 such construction.

The parts shown at 20 are merely ordinary latches for securing the front and rear frame to the ends in crib forming position and do not constitute in themselves a part 110 of our invention.

The details of construction are susceptible

of some modifications without departing from the substance thereof.

What we claim is—

1. A foldable protective crib or bed including a rear frame and channel members fixed thereon parallel to said frame, combined with a cover frame adapted to be slid at its edges into said channel members, rigid hinge pins at the rear corners of said cover frame, said channel members provided with grooves for said pins, seats in the channel members offset and depressed from said grooves to receive said pins when the cover frame is moved to open raised position.
- 15 2. A foldable protective crib or bed including a rear frame and channel members fixed parallel to each other on the rear frame, said members having inwardly

turned lips, combined with a cover frame adapted to be slid at its edges into said channel members, rigid hinge pins at the rear corners of said cover frame, said channel members provided with grooves for said pins, seats in the channel members offset and depressed from said grooves to receive 25 said pins when the cover frame is moved to open position, the inwardly turned lips of said channel members forming stops at their upper ends to support the cover in open raised position.

HAROLD L. CALDWELL.
MARCUS A. CALDWELL.

Witnesses to both signatures:

B. L. GRANT,
BENJAMIN FINCKEL.
